UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed September 16, 1925. Serial No. 56,654.

To all whom it may concern:

Be it known that I, CHARLES C. HANSEN, a citizen of the United States, and a resident of Easton, county of Northampton, and 5 State of Pennsylvania, have invented a certain Double-Drum Hoist, of which the following is a specification accompanied by drawings.

This invention relates to double drum 10 hoists of the type in which two drums are connected to be driven alternately in opposite directions by a reversible motor. Clutch mechanism is provided shiftable automatically into engagement with one 15 drum or the other according to the direction of rotation of the motor.

One object of the invention is to secure 20 a simple and durable clutch mechanism in the form of a jaw clutch which will operate automatically with certainty and precision. Another object of the invention is to reduce the frictional losses throughout the drum operating mechanism of the hoist and a still further object is to protect the drum 25 mechanism and cables by means of a central housing which not only prevents the cables from becoming tangled on the drums, but adds strength to the hoist.

The invention is shown in one of its preferred forms in the accompanying drawings, in which

Figure 1 is a longitudinal sectional elevation of so much of a hoist as will serve to illustrate the invention, taken on the line 35 1-1 of Figure 2 looking in the direction of the arrows,

Figure 2 is a transverse sectional view of the hoist taken on the line 2-2 of Figure 1 looking in the direction of the arrows, and

40 Figure 3 is an enlarged detail side view of the spiral gear on the drum shaft located between the drums on which the main driver in the form of an internally spiralled sleeve is carried.

45 Referring to the drawings any suitable reversible motor may be provided for the hoist, in this instance, a pressure fluid motor of the flat piston type being illustrated comprising the cylinder A, the front head 50 B, the back head C, the piston D adapted to reciprocate horizontally within the rectangular piston space of the cylinder casing A, and the inner piston E adapted to reciprocate vertically within the frame piston D as 55 usual in such engines. The resolution of

forces produced by the pistons impart rotation to the crank F having the crank pin G connected to the inner piston E and thus rotates the motor shaft H in one direction or the other in accordance with the manipulation of the throttle valve handle J, suitably connected to operate a reversing valve K in the front head B. For convenience of construction an intermediate casing L forming a part of the motor casing forms a 60 housing for the counterweight O connected to the motor shaft H and the different parts of the motor casing, including the casing L, are held together by suitable bolts P. A ball bearing Q is provided for the 65 crank pin G and a ball bearing R is provided in the motor back head C for the motor shaft H.

At the opposite end of the motor shaft H is located a gear box S supporting the outer 70 end of the motor shaft in a ball bearing T and containing suitable reduction gearing for connecting the motor shaft to the driving connections for the drums U and V. The gear box S is provided with a cover 75 plate W having caps X and Y for convenience of assembly.

A rotatable hollow center bearing Z around the motor shaft H forms a drum shaft on which the drums U and V are rotatably mounted and ball bearings a and b are provided for the drum shaft in the intermediate casing L and gear box S respectively. Bearing sleeves c and d are provided on the drum shaft for the drums and 80 spacing washers e, f, g, and h are located at the ends of the bearing sleeves. The drums are provided with the usual ropes or cables j and k forming the haulage and tail ropes in accordance with the usual operation of such hoists.

85 A central protective housing o connects the motor casing and the gear box and may be secured to said members in any suitable manner as by means of the screws p and q. 100 This protective housing is cylindrical in form, shown more particularly in Figure 2, and is provided with suitable apertures r and s for the cables j and k respectively. Only sufficient clearance is provided between 105 the drums and the protective housing o to permit rotation of the drums so that the cables cannot ride up over the drum flanges and become tangled. This central protective housing is conveniently provided 110

with a clamping device *t* for clamping the hoist to a shaft *u*.

The drum shaft *Z* is provided with a spiralled gear *v* between the drums and an internally spiralled sleeve *w* cooperates with said spiral gear and forms a main driver for the drums having oppositely facing teeth or jaws *x* and *y* at its sides. These teeth may conveniently be formed on a ring *3* suitably secured to the sleeve *w* as by means of the screws *4*. The teeth *x* and *y* on the main driver are adapted to cooperate alternately with the teeth or jaws *5* and *6* on the drums *U* and *V* respectively, which drum teeth *5* and *6* form drum drivers. The main driver or sleeve *w* is moved longitudinally with relation to the drum shaft in one direction or the other according to the direction of rotation of the motor and in order to insure this longitudinal movement of the drum driver, a brake in the form of a shoe *7* (Figure 2) is provided for the main driver. The shoe *7* may be pivoted at *8* on a brake beam *9* pivotally hung from the pin *10* inside the protective housing *o*. The lower end of the brake beam is adapted to be pressed toward the main driver by means of the spring *12* seated in the socket *13* in the lower portion of the central housing *o*. The socket *13* is slotted at *14* to receive the end of the brake beam and centering the same. A cap *15* is secured over the socket *13* as by means of the bolts *16*.

Operative connections are provided between the motor shaft *H* and the drum shaft *Z* and in this instance the drum shaft *Z* is provided with the large internal gear *17* and the motor shaft is provided with the pinion *18* meshing with the intermediate gear *19* on

the countershaft *20* to which is also connected the intermediate pinion *21* meshing with the internal gear *17*. By this means rotation of the motor shaft *H* in one direction or the other will cause corresponding rotation of the drum shaft *Z* and will cause the main driver *w* to be moved longitudinally on the spiralled gear *v* to bring the clutch teeth *x* or *y* into engagement with the teeth *5* or *6* on the drums. In Figure 1, the main driver is shown in neutral position and when the main driver is in engagement with the drum driver of one drum which becomes the haulage drum, the other drum is loose on the other shaft and becomes the tail rope drum and vice versa.

I claim:

A double drum hoist, comprising a motor casing and reversible motor, a motor shaft extending from the motor, a gear box at the opposite end of the motor shaft, a central protective housing connecting said motor casing and gear box and having openings for the drum cables, a rotatable center bearing around said motor shaft forming a drum shaft, drums rotatable relatively to said drum shaft, a spiral gear on said drum shaft between the drums, an internally spiralled sleeve on said gear forming a main driver having oppositely facing teeth at its sides, toothed drum drivers on the drums adapted to cooperate alternately with the main driver according to the direction of rotation of the motor, a brake for said drum driver, and gearing operatively connecting said drum shaft to the motor shaft.

In testimony whereof I have signed this specification.

CHARLES C. HANSEN.
